(57) **CLAIM**

I claim the ornamental design for a toothbrush handle, as shown and described.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the toothbrush handle shown in broken lines are included for the purpose of illustrating unclaimed portions of the toothbrush handle and form no part of the claimed design.
